(57) **CLAIM**

The ornamental design for a penlight, as shown and described.

DESCRIPTION

FIG. 1 is a perspective view of the penlight showing the front and right side of our new design;

FIG. 2 is a front view of the penlight of FIG. 1;

FIG. 3 is a bottom view of the penlight of FIG. 1;

FIG. 4 is a left side view of the penlight of FIG. 1, the right side view is a mirror image of the left side view and is therefore not shown;

FIG. 5 is a top view of the penlight of FIG. 1; and,
FIG. 6 is a rear view of the penlight of FIG. 1.
